APPARATUS FOR ELECTROMAGNETOSTRITIVE TRANSMISSION AND RECEPTION

George Washington Pierce, Cambridge, Mass.

Original application November 19, 1930, Serial No. 496,809. Divided and this application August 2, 1933, Serial No. 683,349. In Canada December 31, 1927.

18 Claims. (Cl. 177—386)

The present invention relates to the transmission and reception of intelligence, using sound as the agency of communication, and more particularly to communication by sound through air, water, or other dense media. The present application is a division of application Serial No. 496,809, filed November 19, 1930, and a continuation in part of application, Serial No. 158,452, filed January 3, 1927, which matured, on March 11, 1930, into Letters Patent No. 1,750,124.

A feature of the invention is the use of tuned magnetostrictive vibrators. Magnetostrictive vibrators are constituted of a magnetostrictive core disposed in an electromagnetic field, such as may be produced by a coil or winding in an electric circuit.

The invention will be explained in greater detail in connection with the accompanying drawing, in which Fig. 1 is a diagrammatic view, partly in section, of apparatus and circuits constructed and arranged to illustrate a principle of the present invention, the section being taken upon the line 4—4 of Fig. 2, looking in the direction of the arrows; Fig. 2 is an elevation of the same; and Fig. 3 is a diagrammatic view of a transmitting-and-receiving system according to the present invention, it being understood that either end of the system may be operated either to transmit or to receive.

A plurality of rigid cores 2 of highly magnetostrictive material, are shown in Fig. 1, disposed side by side and spaced from each other, and each axially positioned in, and driven by, an inductive and resistive, energizing, field solenoid coil 22. The cores 2 all have substantially the same natural period of mechanical vibration. When stimulated magnetically by the fields of their respective coils 22, the cores 2 become slightly mechanically deformed or distorted by magnetostriction. The resulting increment of deformation may be a lengthening, or a shortening, or some other distortion, depending on the material and on the polarity of the increment of the magnetic field. Conversely, when the cores 2 are mechanically deformed or distorted, they will react or respond magnetically by magnetostriction with an increment of magnetization depending upon the nature of the preexisting magnetic field and the mechanical deformation. The mechanical deformation is produced by exciting reversible internal stresses in the core and the core readily recovers upon the withdrawal of the deforming forces.

The cores 2 may be in the form of tubes, or rods, or they may be otherwise constructed, as

explained in the said Letters Patent. As is also described in the said Letters Patent, they are preferably of nickel, nickel-steel, nickel-copper, nickel-cobalt, chrome-nickel, chrome steel, or of any other metal element or alloy characterized by 5 comparatively large magnetostrictive effects and comparatively low vibrational decrement. By proper choice of length and other dimensions, the apparatus may be made applicable to systems of high or low frequency within a range 10 that may extend from a hundred cycles to hundreds of thousands of cycles. The system finds particular value at superaudible frequencies, the period of the said vibration and the consequent sound wavelength transmitted or received being 15 small enough so that the system shall be directly discriminating as to the sound. The diaphragm 58 is thus a directive diaphragm. The cores are preferably free from contact with the coils, so as to reduce friction, which would prevent free vibration.

The present invention provides a novel, mechanical, vibratory system, comprising the magnetostrictive cores 2 and a diaphragm 58, for use as a sonic oscillator in the production and reception of sounds of any desired frequency, particularly high frequencies, for sonorously communicating through air, water, or other dense media in which the diaphragm is positioned. The cores 2 are shown attached at their ends to one or 30 more diaphragms 58 at separated, spaced positions along a circle, but they may be positioned over substantially the whole extent of the diaphragm 58. In either case, the cores may add to the elastic forces acting on the diaphragm 58 35 and contribute to the period of vibration of the mechanical system constituted of the diaphragm and the cores. The cores 2 may serve also, partly or wholly, as elastic supports for the diaphragm 58, in the event that the diaphragm 58 is not 40 otherwise supported. The distances between the said spaced positions of the cores 2 should be small relatively to the wavelength of sound in the sound-conveying medium, in order that the vibrator shall be directly discriminating as 45 to the sound. The diaphragm 58 constitutes a wall that is actuated by, or that actuates, the cores 2, and that may be positioned, for propagating elastic vibrations, in sonorous relation with a sound-conveying medium, such as 50 air, or the water of the ocean, and constitutes a sound-radiating face for transmission purposes, and a sound-receiving face for reception. The cores 2 effectively cooperate with the diaphragm 58, through their magnetostrictive expansion and 55

contraction, to interchange energy with the sound-conveying medium. One of the faces 58 may be a rigid supporting plate, if desired, the other face 58 only serving as a transmitting or receiving diaphragm. The magnetostrictive vibrator may be orientable as a unit, so as to cause the diaphragm 58 to assume any desired direction, or it may be fixed.

The coils 22 may be connected together, either 10 in parallel or in series, as desired. The fields of adjacent coils 22 may be reversed, so that the lines of force may go to the right through one set of cores 2, and to the left through the alternately placed set of cores 2. Conductors 12 and 15 14 connect the cores 2 in series with a source of alternating electromotive force, such as an alternating-current generator 16, for passing an actuating periodic current through the coils 22. Other, more complicated, sources of alternating 20 current are illustrated in other figures of the above-entitled Letters Patent. A local battery 18, in series with the source 16 and the windings 22, applies a steady magnetizing field to the cores 2, over which the alternating field produced 25 by the generator 16 is superposed, so as to polarize the cores 2. The alternating field is preferably smaller than the steady field, in order that the combined fields may not, at any time, fall to zero. The battery may be dispensed with, and 30 the cores may be magnetized electromagnetically by a local source, or they may be permanently magnetized, instead, or the battery and permanently magnetized cores may be employed together. The magnetizing current may be passed 35 through auxiliary coils, if desired.

If the current or voltage in the coils 22 is alternating, the electromagnetic field created thereby will also be alternating. The cores 2 will, therefore, increase and decrease in length (let us say) 40 many times a second, every variation in the current producing its stimulative effect on the cores 2, and every deformation of the cores producing their reaction response upon the current. The cores 2 will, in consequence, vibrate mechanically by magnetostriction, contracting and 45 expanding lengthwise to and from nodal points in an intermediately disposed, nodal plane. In an intermediate plane, parallel to and between the diaphragms 58, the cores 2 execute no appreciable movement; the two diaphragms 58 may, however, move in opposite directions to and from each other. As the cores 2 are spaced from each other, they are free to expand and contract sidewise at their nodal planes, in a direction 50 perpendicular to the before-mentioned, lengthwise vibration of the cores 2. The cores thus vibrate freely, with a period of vibration equal to the period of the alternating electromotive force. Ordinarily, these vibrations will 55 be quite small. When the alternating frequency is close to, or substantially the same as, the natural frequency of mechanical vibration of the system 2, however, the amplitude of vibration of the cores, though still small, becomes 60 relatively quite large. The cores 2 will then react magnetostrictively on the coils to render their consumption of power critical as to frequency for frequencies near the resonant frequency of the system. The vibrations of the dia- 65 phragm 58 will be correspondingly great. By proper choice of length and other dimensions, as before stated, the cores 2 may be proportioned effectively to transmit vibrational stresses lengthwise of the cores 2 to and from the dia- 70 phragms 58. Of course, there will usually be

more than one specific frequency of magnetization at which the system will thus resonate; for in addition to a natural fundamental frequency of mechanical vibration, the system has also predetermined, natural frequencies of mechanical vibration determined by the operation of the cores in harmonic modes, as is explained more at length in the said Letters Patent, and it will be sufficient here to remember that the operation described herein is equally applicable to the 10 fundamentals and their overtones.

As each core 2 is of relatively small, cross-sectional area, the total aggregate of cross-sectional areas of the metal of the magnetostrictive cores 2 is but a small fraction of the whole 15 extent of the area of the diaphragm 58 over which the cores are disposed, as illustrated, owing to the spaced points at which the cores 2 are affixed to the diaphragm 58. As the cores 2 are of such small, cross-sectional areas, it is relatively easy to compress and expand them, as a unit. The forces exerted by the cores 2 on the diaphragm 58 are, therefore, small compared to what they would have been had the cores 2 been packed closely together. A relatively high amplitude of vibration of the diaphragm 58 is thus permitted, together with good matching of the mechanical constants of the vibratory unit with the mechanical constants of the water. It is not necessary to pack the driving cores 2 continuously and closely together, because ample power is obtainable, notwithstanding that the cores 2 are spaced. The impressed voltage may be divided between the cores 2, particularly if their windings 22 are connected in series, though this 30 is also possible when the coils 22 are connected in parallel. As the vibration amplitude of a magnetostrictive core is limited only by the magnetic properties of the magnetostrictive material, furthermore, it is possible, by proper mechanical design, to transmit relatively tremendous electrical power to the diaphragm 58.

The mechanical system is tuned to the desired frequency, in the medium in which it is to be used. To get the maximum amplitude of the 45 previously designed vibrator, the electrical characteristics of the circuit will also be properly tuned, so as to have a substantially zero reactance for the natural period of mechanical vibration of the vibrator by suitably tuning the 50 generator 16. By thus tuning the mechanical and the electrical systems to the same period into resonance with each other, the current or voltage of the transmitter or the receiver becomes enormously increased, so as resonantly to enhance, 55 very greatly, the interconversion of sound and electric energy through the diaphragm 58, resulting from the magnetostrictive interaction between the diaphragm and the cores 2; such interaction resulting in actuation of the dia- 60 phragm 58 by the vibration of the cores 2, and the cores 2 being vibrated in response to the actuation of the diaphragm. The diaphragm 58 and its cores 2 may be so designed as to elasticity, 65 length and other dimensions, and associated mass, as to have, as a unit, a natural period of mechanical vibration resonant to the frequency of the periodic current in the coils 22. The vibrator comprising the diaphragm 58 and its cores 2 is actuatable as such unit. A yielding, cylindrical band 60 forms, with the diaphragms 58, a chamber in which the coils 22 are contained, which chamber is then sealed against the entry 70 of water when submerged. The chamber forms 75

a rotatable, or orientable, submerged housing, or it may be fixed.

The novel vibratory system of the present invention is thus constituted of a plurality of magnetostrictive bodies 2 separately dimensioned and tuned, in conjunction with the diaphragm 58, to the frequency of the energizing coils 22, for resonantly cooperating synchronously with the diaphragm 58 through their resonant expansion and contraction in response to the action of the energizing coils 20, to interchange electric and sound energy with the sound-conveying medium. By their magnetostrictive expansion and contraction, under the action of currents in the coils 22, the cores 2 will cooperate with the coils 22 to vibrate the diaphragm means to produce radiation of sound into the medium. By their expansion and contraction in response to the incidence of sound in the medium upon the diaphragm means, the cores 2 will cooperate with the coils 22 to generate electric voltages in the coils 22. A multiple-unit of this character will produce greater power than a single unit of corresponding area, and is freer from eddy-current and hysteresis losses, besides being more flexible, so as more easily to conform elastically to the natural medium in which it is operating. The number of magnetostrictive elements, their distribution and their lengths are of magnitudes suitable to easy adjustment for a predetermined resonant system designed to operate at any given frequency, within a wide range as, for example, 10,000 or 40,000 cycles per second. The distribution of driving members permits the ready radiation and distribution of heat, and lends itself to the use of large amounts of power. With thirty seven magnetostrictive driving elements, more than a kilowatt of power can be supplied to the system at 30,000 cycles per second; and, by a larger number of elements, proportionally larger power may be used. The multiple-driven diaphragm is elastically supported at properly spaced, relatively small, distributed areas, capable of sharp and effective tuning, with a large radiating face, and the system has low, mechanical, internal-power losses, capable of high rigidity, or of a rigidity adaptable to the medium in which it is used, by the choice of areas and distribution of driving elements. The system is also characterized by great durability, constancy, and high efficiency. The magnetostrictive drive produces an elasticity and rigidity determined in large part by the driving rods or tubes themselves. A distribution of these members over the face of the diaphragm supplies rigidity to it at a multitude of points and insures a more uniform elasticity for the whole radiating diaphragm.

A sending-and-receiving system is illustrated in Fig. 3, using sound as the agency of communication, the transmitting and the receiving systems both having space-current oscillators. The transmitting system is designed for low decrement, and comprises a vacuum tube 74, the output circuit of which, between the filament or cathode 26 and the plate or anode 28, is provided with a coil 76 that is coupled to a coil 78. The grid is shown at 32. The coil 78 is connected in circuit with a tuning condenser 92 and the energizing coils 22 of a suitably oriented, magnetostrictive vibrator like that illustrated in Figs. 1 and 2. The coils 22 are thus connected with the coil 76 in the output circuit of the space-current device 74. The vibrator may be polarized by a parallel feed consisting of a source 93 of direct or alternating potential, and containing a choke coil 94 for

confining the oscillatory current to the circuit containing the energizing coils 22. The energy of the vacuum tube 74 is thus magnetostrictively transmitted to the sound-radiating diaphragm 58. At high frequencies, this diaphragm 58 of the transmitting system directively transmits along a straight line to the diaphragm 58 of the receiving system.

The supersonic sound waves so directly radiated are received by a suitably oriented sound-receiving vibrator of a receiving system. The energizing coils 22 of the receiving vibrator are connected in circuit with a tuning condenser 95 and a coil 84, a choke coil 97 and a potential source 99 being provided similar to the elements 94 and 93. The diaphragm 58 of the receiving system is thus magnetostrictively associated with the coil 84 which is coupled to a coil 86 in the input circuit of a receiving vacuum tube 88. The tube 88 may have an amplifier for amplifying the energy of the unitary vibrator, so as to enhance the received signals and reduce the electrical decrement of the circuits, and that is connected with a telephone 90 for detecting oscillatory electric currents in the system. Additional tuning condensers 98 and 100 may be employed for tuning the output circuits of the tubes 74 and 88 of the transmitter and the receiver respectively. The generator and associated parts will, as before, be electrically tuned. 30

The term "sound", as used herein, includes not merely audible sound, but all vibrations of a similar nature, including superaudible vibrations. If the sound frequency employed is above the audible range, the heterodyne principle may be used to render the signal audible. Instead of the inductive coupling shown in Fig. 3, other methods of coupling used in related arts may be employed.

It will readily be understood, without further description, that the coils 22 of a single vibrator like that shown in Figs. 1 and 2 may be connected either to a transmitting or a receiving apparatus, as by means of suitable switching arrangements and, indeed, that each such apparatus may, in itself, be used either as a sending or a receiving apparatus. Other modifications, too, will be obvious to persons skilled in the art, and all such are considered to fall within the spirit and scope of the present invention, as defined in the appended claims. 50

What is claimed is:

1. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, the diaphragm being adapted to be positioned in relation to a sound-conveying medium for sonorously inter-communicating energy with the medium by means of its sonorous vibration, the diaphragm having a restricted area to which its sonorous vibration is confined, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to pro- 75

duce radiation of sound into the medium, and to cooperate with the coil means, by their expansion and contraction in response to the incidence of sound in the medium upon the diaphragm, 5 to generate electric voltages magnetostrictively in the said coil means.

2. A sound transmitter having, in combination, a support, a mechanical vibratory system comprising a diaphragm and a plurality of cores of 10 highly magnetostrictive material affixed to the support and the diaphragm at separated, spaced positions, the diaphragm being adapted to be positioned in relation to a sound-conveying medium to produce radiation of sound into the medium by means of its sonorous vibration, the diaphragm having a restricted area to which its sonorous vibration is confined, and coil means magnetostrictively cooperative with the cores, the aggregate cross-sectional area of the metal of 15 the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to produce radiation of sound into the medium.

3. A sound receiver having, in combination, a support, a mechanical vibratory system comprising a diaphragm and a plurality of cores of highly magnetostrictive material affixed to the support and the diaphragm at separated, spaced positions, the diaphragm being adapted to be positioned in relation to a sound-conveying medium for receiving sound from the medium, the diaphragm having a restricted area to which its sonorous vibration is confined, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their expansion and contraction in response to the incidence of sound in the medium upon the diaphragm, to generate electric voltages magnetostrictively in the said coil means.

50 4. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the vibration of the mechanical system, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to operate with the coil means, by their magneto-

strictive expansion and contraction under the action of currents in the coil means, to vibrate the diaphragm to produce radiation of sound into the medium, or to cooperate with the coil means, by their expansion and contraction in response to the incidence of sound in the medium upon the diaphragm, to generate electric voltages magnetostrictively in the said coil means.

55 5. Apparatus for magnetostrictively interchanging electromagnetic energy and sound energy having, in combination, a support, a mechanical vibratory system having a natural period of vibration and comprising a diaphragm and a plurality of cores of highly magnetostrictive material affixed to the support and the diaphragm at separated, spaced positions, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the said natural period of vibration of the mechanical system, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to produce radiation of sound into the medium, or to cooperate with the coil means, by their expansion and contraction in response to the incidence of sound in the medium upon the diaphragm, to generate electric voltages magnetostrictively in the said coil means.

60 6. Apparatus for magnetostrictively interchanging electromagnetic energy and sound energy having, in combination, a support, a mechanical vibratory system having a natural period of vibration and comprising a diaphragm and a plurality of cores of highly magnetostrictive material affixed to the support and the diaphragm at separated, spaced positions, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the said natural period of vibration of the mechanical system, the vibrational constants of the cores cooperating with the diaphragm forces at the respective points of attachment of the cores to the diaphragm in order to facilitate the cophasing of the parts of the diaphragm, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to pro-

duce radiation of sound into the medium, or to cooperate with the coil means, by their expansion and contraction in response to the incidence of sound in the medium upon the diaphragm, to generate electric voltages magnetostrictively in the said coil means.

7. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the vibration of the mechanical system, the cores having substantial equality as to vibration constants, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to produce radiation of sound into the medium, or to cooperate with the coil means, by their expansion and contraction in response to the incidence of sound in the medium upon the diaphragm, to generate electric voltages magnetostrictively in the said coil means.

8. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the vibration of the mechanical system, the cores having substantial equality as to vibration constants and having a comparatively low vibrational decrement to facilitate their vibrations, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to produce radiation of sound into the medium, or to cooperate with the coil means, by their expansion and contraction in response to the incidence of sound in the medium upon

the diaphragm, to generate electric voltages magnetostrictively in the said coil means.

9. Apparatus for magnetostrictively interchanging electromagnetic energy and sound energy having, in combination, a support, a mechanical vibratory system comprising a diaphragm and a plurality of rigid tubular cores of highly magnetostrictive material affixed to the support and the diaphragm at separated, spaced positions, the diaphragm being adapted to be positioned in relation to a sound-conveying medium for sonorously intercommunicating energy with the medium by means of its sonorous vibration, the diaphragm having a restricted area to which its sonorous vibration is confined, and a coil for, and magnetostrictively cooperative with, each tubular core, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with their respective coils, by their magnetostrictive expansion and contraction under the action of currents in the respective coils, to vibrate the diaphragm to produce radiation of sound into the medium, or to cooperate with the respective coils, by their expansion and contraction in response to the incidence of sound in the medium upon the diaphragm, to generate electric voltages magnetostrictively in the respective coils.

10. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, the diaphragm being adapted to be positioned in a body of water for sonorously intercommunicating energy with the water by means of its sonorous vibration, the diaphragm having a restricted area to which its sonorous vibration is confined, the diaphragm and the cores having elastic and mass constants and dimensions of values to cause the diaphragm and the cores both to contribute substantially to the vibration of the mechanical system, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to produce radiation of sound into the water, or to cooperate with the coil means, by their expansion and contraction in response to the incidence of sound in the water upon the diaphragm, to generate electric voltages magnetostrictively in the said coil means.

11. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, the diaphragm being adapted to be positioned in relation to a sound-conveying medium for sonorously intercommunicating energy with the medium by

means of its sonorous vibration, the diaphragm having a restricted area to which its sonorous vibration is confined, and coil means magnetostriictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order 5 to enable the cores to cooperate with the coil means, by their magnetostrictive expansion and contraction under the action of currents in the coil means, to vibrate the diaphragm to produce radiation of sound into the medium, or to 10 operate with the coil means, by their expansion and contraction in response to the incidence of sound in the medium upon the diaphragm, to generate electric voltages magnetostriictively in the said coil means, the cores being separately 15 dimensioned and tuned to cooperate effectively with the frequency of the current in the coil means.

12. Apparatus for magnetostriictively interchanging electromagnetic energy and sound energy having, in combination, a support, a mechanical vibratory system having a natural period of vibration and comprising a diaphragm and a plurality of cores of highly magnetostrictive material affixed to the support and the diaphragm at separated, spaced positions over substantially the whole extent of the diaphragm, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the said natural period of vibration of the mechanical system, the vibrational constants of the cores cooperating with the diaphragm forces at the respective points of attachment of the cores to the diaphragm in order to facilitate piston-wise, 30 co-phasing of the parts of the diaphragm, and coil means magnetostriictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm piston-wise to produce radiation of sound into the medium, or to cooperate with the coil means, by their expansion and contraction in response to the incidence of sound in the medium upon the diaphragm to drive the diaphragm piston-wise, to generate electric voltages magnetostriictively in the said coil means.

13. Apparatus for magnetostriictively interchanging electromagnetic energy and sound energy having, in combination, a support, a mechanical vibratory system having a natural period of vibration and comprising a diaphragm and a plurality of cores of highly magnetostrictive material affixed to the support and the diaphragm at separated, spaced positions along a substantially closed, curved path, the diaphragm being adapted to be positioned in relation to a sound-conveying medium for sonorously intercommunicating energy with the medium by means of its sonorous

vibration, the diaphragm having a restricted area to which its sonorous vibration is confined, the diaphragm and the cores having elastic and mass constants and dimensions of values to cause the diaphragm and the cores both to contribute substantially to the said natural period of vibration of the mechanical system, the vibrational constants of the cores cooperating with the diaphragm forces at the respective points of attachment of the cores to the diaphragm in order to facilitate piston-wise co-phasing of the parts of the diaphragm, and coil means magnetostriictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm piston-wise to produce radiation of sound into the medium, or to cooperate with the coil means, by their expansion and contraction in response to the incidence of sound in the medium upon the diaphragm to drive the diaphragm piston-wise, to generate electric voltages magnetostriictively in the said coil means.

14. Apparatus for magnetostriictively interchanging electromagnetic energy and sound energy having, in combination, a support, a mechanical vibratory system having a natural period of vibration and comprising a diaphragm and a plurality of cores of highly magnetostrictive material affixed to the support and the diaphragm at separated, spaced positions, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the said natural period of vibration of the mechanical system, the vibrational constants of the cores cooperating with the diaphragm forces at the respective points of attachment of the cores to the diaphragm in order to facilitate piston-wise co-phasing of the parts of the diaphragm, and coil means magnetostriictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm piston-wise to produce radiation of sound into the medium, or to cooperate with the coil means, by their expansion and contraction in response to the incidence of sound in the medium upon the diaphragm to drive the diaphragm piston-wise, to generate electric voltages magnetostriictively in the said coil means.

15. Apparatus for magnetostriictively interchanging electromagnetic energy and sound energy having, in combination, a support, a mechanical vibratory system having a natural period of vibration and comprising a diaphragm and a plurality of cores of highly magnetostrictive material

affixed to the support and the diaphragm at separated, spaced positions, the diaphragm being adapted to be positioned in relation to a sound-conveying medium for sonorously intercommunicating energy with the medium by means of its sonorous vibration, the diaphragm being of area having linear dimensions large compared with the effective wave lengths of the intercommunication and having a restricted area to which its sonorous vibration is confined, the diaphragm and the cores having elastic and mass constants and dimensions of values to cause the diaphragm and the cores both to contribute substantially to the said natural period of vibration of the mechanical system, the vibrational constants of the cores cooperating with the diaphragm forces at the respective points of attachment of the cores to the diaphragm, in order to facilitate the cophasing of the parts of the diaphragm at the said effective wave lengths, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to produce radiation of sound of the said effective wave lengths into the medium, or to cooperate with the coil means by their expansion and contraction in response to the incidence of sound of the said effective wave lengths in the medium upon the diaphragm, to generate electric voltages magnetostrictively in the said coil means.

16. Apparatus for magnetostrictively interchanging electromagnetic energy and sound energy having, in combination, a support, a mechanical vibratory system having a natural period of vibration and comprising a diaphragm and a plurality of cores of highly magnetostrictive material affixed to the support and the diaphragm at separated, spaced positions, the cores being adapted to contract and expand lengthwise to and from intermediately disposed nodal planes to produce a piston-wise movement of the diaphragm and being free to expand and contract sidewise at the said nodal planes, the diaphragm being adapted to be positioned in relation to a sound-conveying medium for sonorously intercommunicating energy with the medium by means of its sonorous vibration, the diaphragm having a restricted area to which its sonorous vibration is confined, the diaphragm and the cores having elastic and mass constants and dimensions of values to cause the diaphragm and the cores both to contribute substantially to the said natural period of vibration of the mechanical system, the vibrational constants of the cores cooperating with the diaphragm forces at the respective points of attachment of the cores to the diaphragm, in order to facilitate the piston-wise cophasing of the parts of the diaphragm, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the

action of currents in the coil means, to vibrate the diaphragm piston-wise to produce radiation of sound into the medium, or to cooperate with the coil means, by their expansion and contraction in response to the incidence of sound in the medium upon the diaphragm to drive the diaphragm piston-wise, to generate electric voltages magnetostrictively in the said coil means. 5

17. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, 10 the diaphragm being adapted to be positioned in relation to a sound-conveying medium for sonorously intercommunicating energy with the medium by means of its sonorous vibration, the diaphragm having a restricted area to which its sonorous vibration is confined, and coil means magnetostrictively cooperative with the cores, the aggregate cross-sectional area of the metal of the cores being small relative to the said area of the diaphragm, but the cores being proportioned effectively to transmit vibrational stresses lengthwise of the cores to and from the diaphragm in order to enable the cores to cooperate with the coil means, by their magnetostrictive expansion and contraction under the action of 20 currents in the coil means, to vibrate the diaphragm to produce radiation of sound into the medium, or to cooperate with the coil means, by their expansion and contraction in response to the incidence of sound in the medium upon the 25 diaphragm, to generate electric voltages magnetostrictively in the said coil means, and means yieldingly connecting the support and the diaphragm.

18. Apparatus for magnetostrictively interchanging electromagnetic energy and sound energy having, in combination, a support, a mechanical vibratory system comprising a diaphragm and a plurality of cores of highly magnetostrictive material affixed to the support and the diaphragm at separated, spaced positions, 40 the diaphragm being adapted to be positioned in relation to a sound-conveying medium for sonorously intercommunicating energy with the medium by means of its sonorous vibration, the diaphragm having a restricted area to which its sonorous vibration is confined, and coil means magnetostrictively cooperative with the cores, the aggregate cross-sectional area of the metal of the cores being small relative to the said area of the 45 diaphragm, but the cores being proportioned effectively to transmit vibrational stresses lengthwise of the cores to and from the diaphragm in order to enable the cores to cooperate with the coil means, by their magnetostrictive expansion and contraction under the action of currents in the coil means, to vibrate the diaphragm to produce radiation of sound into the medium, or to cooperate with the coil means, by their expansion and contraction in response to the incidence of sound in the medium upon the 50 diaphragm, to generate electric voltages magnetostrictively in the said coil means, and means yieldingly connecting the diaphragm with the support, the diaphragm and the yielding connecting means constituting a housing in which the cores are disposed. 55

GEORGE W. PIERCE.
